US00D762840S

(12) **United States Design Patent**
Wilkins

(10) **Patent No.:** **US D762,840 S**
(45) **Date of Patent:** **** Aug. 2, 2016**

(54) **IMPELLER**

(71) Applicant: **Stephen Wilkins**, Floyds Knobs, IN (US)

(72) Inventor: **Stephen Wilkins**, Floyds Knobs, IN (US)

(73) Assignee: **WILKINS IP, LLC**, New Albany, IN (US)

(**) Term: **14 Years**

(21) Appl. No.: **29/520,641**

(22) Filed: **Mar. 17, 2015**

(51) **LOC (10) Cl.** **23-04**

(52) **U.S. Cl.** USPC **D23/413; D15/7**
